UNITED STATES PATENT OFFICE.

LOUIS R. RUTHENBURG, OF EAST MOLINE, ILLINOIS.

BOAT.

Application filed July 22, 1926, Serial No. 124,208.

My invention relates to boats and in particular to the construction of the hulls thereof.

It is the object of my invention to provide a simply-constructed boat, capable of being assembled in sections and produced in quantities.

It is the object of my invention to provide a system of reinforcing the construction in such a way as to provide the maximum strength with the minimum weight, together with simplicity of construction, facilitating assembly and manufacture.

Referring to the drawings:

Figure 1 is a side elevation of a boat constructed according to my invention;

Figure 2 is a section on the line 2—2 of Figure 1 looking in the direction of the arrows;

Figure 3 is a section on the line 3—3 of Figure 2 looking in the direction of the arrows.

Referring to the drawings in detail, it will be noted that the boat consists of a plurality of transversely continuous overlapping sections of metal, designated 1, 2, 3, 4 and 5 reading from the bow to the stern.

The rear edge 6 of any given section overlaps the forward rib edge 7 of any succeeding section and may be countersunk therein so that the outer surfaces of the two sections will be flush and the overlapping portion of the succeeding section will be turned up at right angles to its major axis, as at 8, to form a transverse rib.

Thus, I provide, integral with the body sections themselves, ribs located at the points of greatest weakness and by countersinking the preceding section so that the exterior surfaces are flush, I provide a boat body with the minimum of frictional resistance.

If desired, supplementary angular rib members 9 can be provided to supplement the reinforcing of the integral ribs of the sections. Thus, my invention is characterized by a succession of transversely continuous overlapping sections presenting a flush exterior surface and a plurality of integrally formed ribs adjacent the joints of the sections.

In addition to the foregoing, my invention is characterized by having an exterior continuous bow stem and keel member semi-circular in section, designated 10, having diverging flanges 11 adapted to be attached

to the body sections, thereby forming a longitudinal reinforcing rib and keel member combined as well as an integral stem for the bow.

In order to provide a well-defined chine line, I provide exterior angular chine plates preferably extending continuously fore and aft, designated 12. These plates are likewise attached to the sections and serve to hold the sections to one another, just as a keel member so serves.

In my boat, I have provided therefore three groups of elements easily assembled and all mutually supporting to provide a very rigid structure, such as overlapping sections with integrally formed ribs, the keel member and the chine members.

I also provide members extending fore and aft which serve the same reinforcing and connecting purposes and also function as the gunwale, designated 13.

This member is provided with a flange 14 and an overlapping cap member 15 to overlap the ends of the ribs to provide a neat appearance for the boat and to prevent any one being injured on the sharp edges of the ribs where they project upwardly.

It will be understood that I desire to comprehend within my invention such modifications as may be necessary to adapt it to varying conditions and uses.

Having thus fully described my invention, what I claim as new and desire to secure by Letters Patent, is:

1. In a boat, a hull formed of a plurality of successive sections having their transverse edges overlapping one another said sections being formed of a continuous piece of material from one side of the boat to the other so as to form a flush exterior surface.

2. In a boat, a hull formed of a plurality of successive sections having their transverse edges overlapping one another, one section being recessed to receive the edge of the adjacent section to present a flush exterior surface said sections being continuous from one side of the boat to the other.

3. In a boat, a hull composed of a succession of transversely continuous sections having their edges overlapping each one of said sections having an integrally-formed rib on the edge adjacent to the next adjacent section the overlapping edge being turned inwardly in a vertical plane to form the reinforcing rib.

4. In a boat, a hull formed of a succession

- of transversely continuous sections having overlapping edges, and means extending fore and aft of the boat body overlapping said sections to reinforce and connect them together, said means consisting of a keel member, and chine members said keel and chine members being located completely exterior of the exterior portions of the sections without interrupting the continuity of the sections.
- 5 5. In a boat, a hull formed of a succession of transversely continuous sections having overlapping edges, and means extending fore and aft of the boat body overlapping said sections to reinforce and connect them together, said means consisting of a keel member, chine members and a gunwale member said members being so arranged as not to interrupt the transverse continuity of the sections.
- 10 15 6. In a boat, a body consisting of a plurality of successive overlapping sections, each one of said sections having an integrally formed rib adjacent its line of connection with the adjacent section and a plurality of

overlapping longitudinally extending, connecting and reinforcing members adapted to reinforce and hold said sections to one another to form the body, said reinforcing members consisting of a keel member and chine members, said keel member having a semi-circular external surface and said chine members present angular surfaces to provide a sharp chine edge.

7. In a boat, a body consisting of a plurality of transversely continuous successive overlapping sections, the edges of one section being countersunk in the adjacent section to present a flush exterior and each one of said sections having one of its edges formed into a reinforcing rib, a continuous stem and keel piece disposed externally of said sections to connect them to one another and chine pieces located on the exterior of said body extending fore and aft connecting said sections to one another.

45 In testimony whereof, I affix my signature.

LOUIS R. RUTHENBURG.
